Oson W. Smith

United States Patent Office.

ORSON W. SMITH, OF FLINT, MICHIGAN.

Letters Patent No. 106,216, dated August 9, 1870.

IMPROVEMENT IN APPARATUS FOR CARRYING GRAIN, PLASTER, &c., FOR SOWING.

The Schedule referred to in these Letters Patent and making part of the same

To all whom it may concern:

Be it known that I, ORSON W. SMITH, of Flint city, in the county of Genesee and State of Michigan, have invented a new and Improved Mode of Carrying Grain, Plaster, or anything to be sown or planted from the hand, called a seed, grain, and plaster-carrier; and I do hereby declare that the following is a full, clear, and exact description of the construction and operation of the same, reference being had to the annexed drawing making a part of this specification.

The annexed drawing represents my invention in perspective.

A represent the sack, the top of which is bound onto the hoop or rim, B B, for holding the grain or substance to be planted or sown.

B B represent the hoop or rim, bent in such a manner as to fit the form of the person, and sustain and hold open the mouth of the sack.

C C represent a strap or belt, with one end attached to the front end of the hoop or rim, and designed to pass around the neck, with the other end attached to

the opposite side of the rim, in such a place as shall cause it to form a good and perfect support.

D D represent a strap or belt, attached to either end of the rim B B, designed to pass around the waist of the person, for the purpose of keeping the carrier in position.

The manner of using the carrier will be readily seen. When to be sown or planted from with one hand, it will be adjusted on the side or hip of the person. In case it should be desirable to use both hands, it can readily be adjusted to the front of the person, bringing the mouth of the carrier in such position as to give easy access to either hand.

Having thus described my invention,

What I claim as new, and desire to secure by Letters Patent, is—

The herein-described arrangement of the bag A, belts C and D, and hoop B, as herein constructed and combined.
